VACUUM FILLING HEAD

Howard A. Rohdin, Glen Ridge, N. J.

Application June 4, 1948, Serial No. 31,061

3 Claims. (Cl. 141—49)

It is an object of this invention to provide a vacuum type filling machine so far simplified over the prior art as to be of minimum cost.

It is a further object of this invention to provide a machine of the type aforesaid which is capable of handling both sluggish and free flowing materials.

It is a further object of this invention to provide in a machine of the type aforesaid a simple adjustment to permit the machine to deliver a wide range of quantities.

It is a further object of this invention to provide a machine as aforesaid which will be easy to clean and in which a vacuum system is so arranged as to prevent any contamination of the product being handled by any product previously handled.

It is a further object of this invention to provide a machine as aforesaid in which the loss of the product being handled is minimized.

It is a further object of this invention to provide a machine as aforesaid capable of operating at a maximum speed with a minimum duration of the inactive portion of its operating cycle.

It is a further object of this invention to provide a machine as aforesaid which will have maximum accuracy in measuring a predetermined load and which will assure even consistency of the packaging between consecutive packages with a minimum of entrapped air in the package.

The above and other objects will be made clear from the following detailed description taken with the connection in the annexed drawings in which:

Fig. 1 is a section through one form of the improved filling head;

Fig. 2 is a detail of the material gate in the head shown in Fig. 1;

Fig. 3 is a diagram of the electrical and pneumatic hook-up for operating the head of Fig. 1;

Fig. 4 is a view similar to Fig. 1 but showing a modified form of head;

Fig. 5 is a diagram of the electrical and pneumatic hook-up for operating the head illustrated in Fig. 4;

Fig. 6 is a section through still another form of head which is particularly adapted to use in a revolving turret; and

Fig. 7 is a section of a head having a special form of valve.

Certain pulverulent materials are very difficult to bring into compact condition by the ordinary mechanical joggling and squeezing methods. Typical of such materials are cocoa, the so-called "instant coffees," carbon black and many chemicals, pharmaceuticals and cosmetics. It has become customary in handling materials of this type to conduct the filling operation under vacuum so as to minimize the entrapment of air between the particles. Since most of such materials are relatively light and fluffy there must be provided a screen between the source of vacuum and the package, the interior of which is subjected to vacuum during the filling operation. Such screens if of fine enough mesh to be effective rapidly

2

become clogged and, therefore, must be cleaned, usually several times during each filling operation. This has been accomplished in various ways but one of the most effective has been to arrange for a reversal of flow of air through the screens which effects quite thorough cleaning. The present invention is concerned among other things with effecting such a reversal of flow through the screens without, however, any reversal of flow in the ducts making up the vacuum system.

10 In the nature of machines of this class the precise number and type of cycles necessary to deliver a pre-determined quantity of any particular material must be determined empirically. Once this is determined, however, the maintenance of a high level of accuracy as between

15 consecutive packages depends on minimizing the uncontrollable variables. Usually in machines of this class, material starts to flow into the packages as soon as any appreciable vacuum is created within the package. Since initially the package is at atmospheric pressure and the 20 vacuum in the line is in the order of 25", there will be a period of variable flow before anything approximating line vacuum is attained in the package and during this period air may become entrapped in the bottom of the package.

25 The present invention overcomes this by providing a gate between the supply of material and the package and making the opening of the gate responsive to the attainment within the package of substantially line vacuum. This gate is arranged to provide a minimum of space between the level of the gate and the ultimate load line of the package. This is important, particularly in the case of free flowing materials since it minimizes the otherwise variable quantity of material that may be in the air above the load line of the package when the gate is closed.

30 Since it is necessary to shut off the vacuum and, therefore, discontinue filling several times during the filling of a single package in order to clear the screens the overall filling time is determined by the speed with which the vacuum can be shut off, the screens cleaned and the

35 40 vacuum resumed.

As noted above a substantial time is required to establish pressure equilibrium and so far as the total volume involved can be reduced this time is minimized. In the present invention every step is taken as close as possible to the package itself.

Referring now to Fig. 1, there is illustrated a filling head 10 secured to the flange 12 of a hopper 14. The inner wall 16 of the head 10 is sloped to form a continuation of the hopper. In the lower face 18 of the head 50 is formed a gasket 20. There is also an annular groove 22 covered by a screen 24. A vacuum passage 26 and an air passage 28 are formed in the head and communicate with the groove 22.

55 A pair of discs 30 and 32 engage and are fixed to an annular ring 34 formed in the head 10. A valve 36 rests between the discs 30 and 32 and bears on the ring 34. The valve 36 is free to rotate and is secured to a flange 38 which in turn is secured to a shaft 40. A set of openings 42 is formed in the upper disc 30 and these register with

60 similar openings 44 in the lower disc 32. The valve 36 has a similar set of openings 46, which, as shown in Fig. 2, may be placed either in registry with the disc openings to open the valve, or out of registry to close the valve. Moreover, the extent of rotation of the valve 36 will determine the exact extent of valve opening so that various types of materials can be handled.

65 The shaft 40 passes through a stuffing box 48 in a casing 50. Inside the casing 50 the shaft 40 is keyed to a hollow member 52. The member 52 has a bore 54 in which are formed high pitched threads 56. The threads 56 engage mating threads 58 on a cylinder 60 which is itself secured to a shaft 62. The shaft 62 passes through

the base 64 of a cage 66 which is supported on a ledge 68 formed in the casing 50.

Above the base 64 the shaft 62 is squared to fit a square boss 70 formed in the cage 66. A pair of thumb nuts 72 are threaded on the shaft 62 below the base 64 and serve 5 adjustably to limit upward sliding movement of the shaft 62, hence to adjust the extent of rotation of the valve 36 by the engagement of the threads 56 and 58.

At its upper extremity the shaft 62 passes through a plate 74 attached to the cage 66 and engages a pneumatic bellows member 76. Below the top plate 74 and surrounding the shaft 62 is a spring 78. The spring 78 bears at one end on the plate 74 and at the other end on a disc 80 slidably mounted on the shaft 62. A pair of thumb nuts 82 are threaded on the shaft 62 below the 15 disc 80 and serve to adjust tension of the spring 78.

The bellows 76 is secured by a nut 84 to a plate 86 which bears on the upper end of the cage 66. A cup-shaped cap member 88 has threaded engagement with the casing 50 and is secured to the bellows supporting plate 20 86. This tightly encloses all working parts. A vacuum tube 90 connects with the bellows 76 through the nut 84.

The inter-relationship of the above described parts will be made clear by reference to Fig. 3 in which there is indicated a vacuum pump 92 connected through a valve 25 94 with the vacuum passage 26 of the head 10. The valve 94 may be of any desired type and is normally spring closed. It is provided with a solenoid 94' which, when energized, opens the valve 94. The passage 28 of the head 10 connects to the atmosphere through a valve 30 96. The valve 96 also may be of any desired type and is spring biased to a normally open position. A cam 98 is provided for periodic closing of the valve 96. This valve carries a contact 100 which, when the valve is closed by the cam 98, closes contacts 102 to energize the solenoid 35 94' and thus to open the valve 94. The vacuum line 90, which is connected to the bellows 76 has its other end connected to the line 28 of the head 10.

An actual filling operation will now be described. A can or jar to be filled has its mouth pressed into sealed contact with the gasket 20 of the head 10, and rotation of the cam 98 is then started. The cam 98 closes the valve 96 and the contacts 102. This energizes the solenoid 94' and opens the valve 94, thus connecting the head 10 to the vacuum pump 92. As pressure drops in the head 10, it also drops in the line 90 and the bellows 76. When the absolute pressure in the line 90 reaches a level predetermined by the tension of the spring 78 as adjusted by the thumb nuts 82, the bellows draws the shaft 62 upwardly to the limit determined by the engagement 50 of the lower set of thumb nuts with the base 64 of the cage 66. This upward movement of the shaft 62 rotates the valve 36 and allows material to flow into the can or jar.

After an interval determined by the speed and proportions of the cam 98 the valve 96 is allowed to open, and at the same time the valve 94 is closed by the breaking of the circuit of the solenoid 94'. The result is to set up a pressure shock wave in the head 10 which serves to clear the screen 24. This clearing effect is aided by the evacuated space in the container which helps to draw air directly through the screen. Obviously the breaking of the vacuum releases the bellows 76 and closes the valve 36. The cycle may be repeated as often as necessary to fill any given container. Usually two such cycles will suffice. It is clear that the vacuum step should last much longer than the clearing step, which need only be momentary. Valve 96 may be connected to a gas chamber, thereby gassing the contents of the container.

Machines of this class must meet an infinite variety of materials. Some materials will tend to cling to the screens so tightly that the procedure just described will not be sufficient to obtain thorough clearing of the screen. It is to meet such cases that the modifications of Figs. 4 and 5 were devised.

Fig. 4 shows a head 150 having a gasket 152 and an annular groove 154 covered by a screen 156. The groove 154 has a vacuum passage 158 and an air passage 160. The head 150 is also provided with a material valve 162. Thus far the head 150 is identical with the head 10 of Fig. 1. The head 150, however, is provided with a narrow supplemental annular channel 164 running between the groove 154 and the valve 162. This channel 164 has its own vacuum connection 166 and is not screened the connection 166 obviously must not be allowed to intersect either passages 158 or 160 and therefore is shown in dotted outline in Fig. 4.

The operation of the parts described in the preceding paragraph will be understood from a consideration of Fig. 5. Fig. 5 is entirely schematic and shows a vacuum pump 168 connected to a header 170 which leads to a normally open valve 172 which is closed by the energizing of a solenoid 174. The header 170 also connects with a normally closed valve 176 which is opened by a solenoid 178. The valve 172 connects the vacuum pump 168 to the line 158 which evacuates the groove 154 covered by the screen 156. The valve 176 connects the vacuum pump 168 to the duct 166 which evacuates the unscreened auxiliary channel 164. A normally closed valve 180 is opened by a cam 182 and connects the screened groove 154 to the atmosphere through the duct 160. The tube 90 leading to the bellows 76 and its attached rod 60 connects with the duct 160.

In starting condition the valve 172 is open and the valve 180 is closed. As pressure drops within the head 150 the bellows 76 is collapsed by the tube 90 to draw up the rod 60 and open the valve 36 upon the attainment of a predetermined vacuum in the line 90. Material at once is drawn from the hopper 14 into the container to be filled.

At the end of an interval predetermined by rotation of the cam 182 the valve 180 opens to admit atmospheric pressure to the duct 160. This expands the bellows 76, closing the valve 36. At the same time it opens contacts 184 and closes contacts 186. The contacts 184 break the circuit of solenoid 174, hence close the valve 172 which connects the groove 154 with the vacuum pump 168. The closing of contacts 186 energizes the solenoid 178 which opens the valve 176 connecting the unscreened auxiliary channel 164 with the vacuum pump 168. This draws air from the atmosphere through the valve 180, the duct 160 and the screens 156 and clears the screens without, however, reversing any flow except through the screens 156. As the cam 182 continues to move, it closes the valve 180 and the contacts 184 and opens the contacts 186. This reverses the action just described in that it closes valve 176 and opens valve 172, thereby resuming the vacuum withdrawal of material from the hopper 14.

Fig. 6 shows an exceptionally compact modification of this invention which is especially applicable to the operation of a number of filling heads arranged around a turret.

Here the hopper 14 is joined to a head 200 which contains a valve 202 identical to the valve of Fig. 1 and similarly operated. The head 200 has an annular passage 204 covered by a screen 206 and has the usual gasket 208. The passage 204 is connected to a duct 210.

A ring 212 is secured by cap screws 214 to the underside of the head 200 and a generally similar ring 216 is secured by cap screws 218 to the upper side of the head 200. An annular valve 220 surrounds the head 200 and has labyrinth grooves and ridges 222 mating with similar grooves and ridges in the upper ring 216 and has a similar arrangement 224 of labyrinth grooves and ridges mating with the lower ring 212. A gear 226 is formed integral with the valve 220.

A ring 228 surrounds the valve 220 and has formed therein a vacuum channel 230 and an atmospheric channel 232. A sealing ring 234 surrounds the ring 228 and contains a vacuum connection 236 and an atmospheric connection 238. The meeting surfaces of rings 228 and

234 are beveled and contain gaskets 240. A set of labyrinth grooves and ridges 242 are formed between the ring 228 and the gear 226. The sealing ring 234 is secured by cap screws 244 to the upper ring 216 through a gasket 246.

The valve 220 contains one or more passageways 248 which connect the duct 210 leading to the annular passage 204 to the vacuum chamber 230 defined by rings 228 and 234. Other passages, not shown, in the valve 220 serve to connect a duct 250 in the head 200 with the atmospheric chamber 232 also defined by the rings 228 and 234.

It is clear that by properly locating and proportioning the vacuum and atmospheric passages in the valve 220 there can be created precisely the cycle described with reference to Figs. 1 and 3. In turret operation the head 200 revolves around a fixed gear meshing with the gear 226 which has the effect of rotating the valve 220 relative to the head 200 and the rings 228 and 234. This relative movement sequentially connects the passage 204 with vacuum and atmosphere.

It will be clear that the construction just described is equally adaptable to the form shown in Fig. 4 and the cycle described with reference to Fig. 5. Since this would involve only the addition of an unscreened annular channel in the head 200 and an auxiliary duct for occasional communication with the vacuum chamber 230.

In Fig. 7 there is illustrated a special form of valve which may be used with either of the forms of heads shown in Figs. 1 and 4. This valve has particular utility where the material being handled is gritty or abrasive. In Fig. 7 there is a head 300, attached to a hopper 302. A screened channel 304 is formed in the head 300. A valve 306 fits in the mouth of the head and is secured to a rod 308 which is attached at its other end to a diaphragm 310. The diaphragm 310 is supported by the hopper 302 by means of a spider 312, and is connected to the vacuum system by a line 314. Since the amplitude of movement is small in this case, and since the valve 306 must be lifted not only against the weight of material in the hopper but also against the vacuum in the container, the use of a diaphragm rather than a bellow is distinctly indicated.

What is claimed is:

1. In a vacuum type filling machine: a head having a screened channel and a material inlet adjacent thereto; a duct for connecting said screened channel to a source of sub-atmospheric pressure; a second and separate duct for connecting said screened channel to a source of at 50

least atmospheric pressure, each of said ducts having an independent valve; means for operating each of said valves; and means controlling said valve operating means to assure that when one valve is open the other is closed, 5 and means for actuating said valve operating means one or more times prior to the completion of a filling operation.

2. In a vacuum type filling machine: a head having a screened channel and a material inlet adjacent thereto, 10 a duct for connecting said screened channel to a source of sub-atmospheric pressure, a second and separate duct for connecting said screened channel to a source of at least atmospheric pressure, each of said ducts having an independent valve, means for operating each of said valves and means controlling said valve operating means to assure that when one valve is open the other is closed, a supplemental vacuum channel, a duct for connecting said channel to a source of vacuum, a valve in said duct, means for operating said valve and means controlling 15 said valve operating means to assure that said valve is open only when the valve in the first vacuum duct is closed and the valve in the at least atmospheric pressure duct is open.

3. In a vacuum type filling machine for filling containers with pulverulent material: a filling head having a gasket to make sealing contact under vertically exerted pressure with the mouth of a container to be filled, said head having a vacuum channel and an inlet for pulverulent material, said vacuum channel and inlet being surrounded by said gasket; a material supply hopper mounted directly above and connected to said inlet by a passage in line with said container to be filled; a valve in said passage; means biasing said valve to closed position; vacuum means for overcoming said biasing means 30 to open said valve, and being uninterruptedly connected to said vacuum channel.
